[57] CLAIM

The ornamental design for a light module for suspended lighting fixture unit, as shown and described.

DESCRIPTION

FIG. 1 is a perspective view of a light module for suspended lighting fixture unit taken from the bottom, left, and front showing our new design;

FIG. 2 is a front elevational view thereof, the rear elevational view being the mirror image thereof;

FIG. 3 is a left side elevational view, the right side being the mirror image thereof;

FIG. 4 is a bottom plan view thereof;

FIG. 5 is a top plan view thereof;

FIG. 6 is a view similar to FIG. 5, albeit with a light unit shown in dotted lines; and,

FIGS. 7-10 are views similar to FIG. 1, albeit of second, third, fourth, and fifth embodiments, the difference being in the side to side dimension.

The broken line representation of a light unit in FIG. 6 is for purposes of illustration only.
